UNITED STATES PATENT OFFICE.

ROBERT C. HOPKINS, OF ALLIANCE, OHIO.

LIQUID-FUEL BURNER.

Application filed April 4, 1924. Serial No. 704,170.

The invention relates to liquid fuel burners of the type in which the liquid fuel is atomized by air or other fluid pressure.

The objects of the invention are to provide a burner of this character in which the liquid fuel is ejected in a thin film at nearly right angles to the blast of air or other fluid and against a toothed ring which serves to further break up the fuel.

10 The above and other objects may be attained by constructing the burner in the manner illustrated in the accompanying drawing, in which—

Figure 1 is a longitudinal, sectional view 15 through a burner embodying the invention; and

Fig. 2, an end elevation of the oil tube and ring with the valve removed.

Similar numerals refer to similar parts 20 throughout the drawing.

The burner comprises the L-shaped casing 1, having the upper neck 2 to which an air blast pipe 3 is connected, and the reduced neck 4 at one end to receive the oil tube 5.

25 The oil tube is held in adjusted position within the burner casing as by a set screw 6 and extends longitudinally through the casing to a point near the outlet end 7, to which may be connected any suitable tubular member 8 in which the combustion takes place.

The outer end of the oil pipe 5 may be threaded as at 9 for the connection of a coupling 10, to which the oil supply pipe 35 11 is attached. As illustrated in the drawing, this coupling may be in the form of a T, and a threaded plug 12 may be provided for closing the outer end.

40 The inner end of the oil tube 5 terminates in the conical portion 13 having the reduced valve seat 14 at its extremity. The conical valve 15 is mounted upon the stem 16 axially slidably located through webs 17.

A coil spring 18 is located around the stem 45 between one of the webs 17 and the shoulder 19 fixed upon the outer end portion of the stem, for the purpose of normally holding the valve 15 seated upon the seat 14 at the tapered end of the oil tube.

50 A ring 20, triangular in cross section, is located concentrically with the tapered end of the oil tube 5, being preferably formed integral therewith and connected as by the

webs 21. This ring is provided with the radial slots 22 located through the reduced 55 or tapered side thereof.

In the operation of the burner, oil is supplied through the pipe 11 into the tube 5 and air under pressure is supplied through the pipe 3 into the casing 1. The pressure 60 of the oil will unseat the valve 15 sufficiently to allow the oil to pass out in the form of a thin disk shaped film directed toward the slotted ring 20.

The air passing around the inside of the 65 ring toward the tube 8, breaks up the greater part of this film of oil, mixing the atomized oil with the air and carrying the same into the combustion tube 8.

The remainder of the oil striking the slot- 70 ed ring 20, will be further broken up and any particles thereof which pass through the slots in the ring, will be caught in a concentric current of air passing around the outside of the ring and will be properly 75 mixed with the air as it passes into the combustion tube 8.

I claim:—

1. A liquid fuel burner comprising a casing, an air conducting pipe communicating 80 with the casing, an oil conducting tube extending into the casing, a spring pressed valve normally closing the inner end of the oil tube and a slotted ring spaced from the valve and the interior of the casing and co- 85 axial therewith the valve being arranged to deflect and break up the oil against said ring.

2. A liquid fuel burner comprising a casing, an air conducting pipe communicating 90 with the casing, an oil conducting tube extending into the casing, a spring pressed valve normally closing the inner end of the oil tube, a slotted ring spaced from the valve and the interior of the casing and coaxial 95 therewith, and means for adjusting the tube longitudinally within the casing the valve being arranged to deflect and break up the oil against said ring.

3. A liquid fuel burner comprising a cas- 100 ing provided with an outlet opening, an air conducting pipe communicating with the casing, an oil tube extending into the cas- 105 ing, a spring pressed valve for normally clos- ing the inner end of the oil tube, a ring spaced from the valve and fixed to the oil

tube, and means for adjusting the oil tube and ring with reference to the outlet opening the valve being arranged to deflect and break up the oil against said ring.

5. A liquid fuel burner comprising a casing provided with an outlet opening, an air conducting pipe communicating with the casing, an oil tube extending into the casing, a spring pressed valve for normally closing

the inner end of the oil tube, a slotted ring ¹⁰ spaced from the valve and fixed to the oil tube, and means for adjusting the oil tube and ring with reference to the outlet opening the valve being arranged to deflect and break up oil against said ring. ¹⁵

In testimony that I claim the above, I have hereunto subscribed my name.

ROBT. C. HOPKINS.
